FIG. 1 is a front, top, right side perspective view of a license plate frame having stud belt features showing my new design;
FIG. 2 is a front elevation view thereof;
FIG. 3 is a rear elevation view thereof;
FIG. 4 is a left side elevation view thereof, the right side elevation view being the same; and,
FIG. 5 is a bottom plan view thereof, the top plan view being the same.

The broken line showing of the mounting holes is for illustrative purposes only and forms no part of the claimed design.
